UNITED STATES PATENT OFFICE.

WILLIAM H. TRISSLER, OF CLEVELAND, OHIO.

IMPROVEMENT IN PLOW-POINTS.

Specification forming part of Letters Patent No. 177,973, dated May 30, 1876; application filed April 7, 1876.

To all whom it may concern:

Be it known that I, W. H. TRISSLER, of Cleveland, in the county of Cuyahoga and State of Ohio, have invented certain new and useful Improvements in Plow-Points, of which the following is a specification:

The nature of my invention consists in the construction of a plow-point, to be placed over and fastened to the ordinary point of a plow, as will be hereinafter more fully set forth.

In order to enable others skilled in the art to which my invention appertains to make and use the same, I will now proceed to describe its construction and operation, referring to the annexed drawing, which forms a part of this specification, and in which—

Figure 1 is a perspective view of my invention. Fig. 2 is an old plow-point. Fig. 3 is the new plow-point; and Fig. 4 is a longitudinal section, showing the new point attached to the old point.

A represents the plow-point, having its end made solid, and its rear portion is made hollow, open at the rear or upper end, and formed with a slot, *a*, at each side. On the inside of the hollow portion of the point A are formed ribs *b*, as shown. B represents the ordinary plow-point, which has a notch, *d*, made in

each side, when it is desired to apply the hollow point A.

In applying or putting on the new point A, the old point B is first heated, and then inserted in the hollow point A. Paper is then wrapped around the same, and melted soft metal is poured in at the upper end, between the two points, the paper preventing the metal from running out through the holes *a*. When the soft metal cools it forms a lock between the old and new points by passing into the slots *a* and notches *d*, the ribs *b* also assisting in keeping the old point to its place.

Having thus fully described my invention, what I claim as new, and desire to secure by Letters Patent, is—

The hollow plow-point A, provided with side slots *a* and interior ribs *b*, in combination with an ordinary plow-point, B, provided with notches *d*, substantially as shown and described.

In testimony that I claim the foregoing as my own I affix my signature in presence of two witnesses.

WILLIAM H. TRISSLER.
